UNITED STATES PATENT OFFICE

JESSE A. B. SMITH, OF STAMFORD, CONNECTICUT, ASSIGNOR TO UNDERWOOD ELLIOTT
FISHER COMPANY, OF NEW YORK, N. Y., A CORPORATION OF DELAWARE

TYPEWRITING MACHINE

Application filed November 11, 1927. Serial No. 232,513.

This invention relates to fan-fold type-writing machines, and more particularly to the typing and manipulating therein of a fan-folded web of narrow short forms or slips, together with a fan-folded web having forms wider and longer than the narrow forms.

One feature of the present invention is a new organization of means for the handling and typing of two fan-folded webs simultaneously in the machine.

Another feature relates to the carbon-stripping, whereby the carbons are stripped from both sets of webs without any direct handling of a condensed day-book record-web.

Still another feature relates to the means for guiding and holding the day-book record-web on the front paper-table during the operation of the machine, said means being readily displaced to permit the severing of each typed condensed record-web form.

It will be understood that stock-brokers' offices are required to send a condensed record of each day's sales to the clearance department of the stock exchange. This daily report is required to be made on forms, sometimes called day-book-sheets, of prescribed size. Additional copies of the above-mentioned day-book-sheets are made for the different departments of the stock-broker's office. A statement of each sale must be manifoldeled on a set of short form-bearing slips, one of which forms goes to the customer, the remainder being distributed among the various departments of the office.

It is an object of the present invention to provide means for rapidly and efficiently preparing these two kinds of multiple statements and multiple day-book-sheets in a typewriting machine, similar to that enclosed in the Wernery & Smith Patent No. 1,132,055, dated March 16, 1915.

The invention includes a web of short statement forms, upon which one line only is to be typed and then the typed forms torn off, and a condensed record fan-fold web having day-book forms of greater width and length than the statement-forms, and which consists of several plies that are torn off from time to time. This condensed record is pro-

vided with a heading and other data. The short, narrow form consists of several plies and is also provided with a heading. The short form is so short that, after one line has been typed thereon and the form line-spaced together with the record-web, there would not be a sufficient amount projecting above the knife to enable an operator to grip the same and pull it forward. For this reason, the knife-handle is placed at a convenient position so that an operator can swing the knife down and then grip the form, displace the platen, and pull the form forward over the stationary record-form.

The record-web is first interleaved with carbons, and is then fed around the platen, and is positioned for its first line of typing. In this position, it is gripped by clamps provided for this purpose. The narrow web is then interleaved with carbons and is fed around the platen and by means of my invention may be collated to proper position on top of the record-web. After having typed one line, the operator releases novel clamps for the record-web by means provided for this purpose, and then line-spaces the whole together, after which the clamps are again moved to clamp the record-web. The knife is then swung down to enable the operator to grip the top of the small web, the platen displaced, and the short web pulled forward to a tearing-off position determined by a gaging bar. For side gaging the small web during this forward movement, the gaging bar is provided with side edge gages mounted thereon, which are adjustable for different web-widths. When the multiple-ply record-web is fed forward, it is contrived to feed said web behind the side-edge gages and behind the gaging bar to rest upon the record-paper-table, which with said side-edge gages forms a web-course for the record-web. For this purpose, the gage-bar has a handle rigidly attached thereto, so that, by operating this handle, the bar will be rotated and will swing the side edge gages up, thereby permitting the record-web to be entered under the gages. To assist in keeping the record-sheet close against the paper-table at its middle portion, the gage-bar also carries a finger which acts

similarly to the two gages on the side, that is, said finger co-operates with said side gages to guide the record-web over the paper-table. The clamps are individually provided with spring-members so that each clamp will exert pressure on the multiple-ply record-web independently of the other. The clamps grip the record-web at its side margins, and the individual pressure of each clamp enables it to grip the more or less bulky web firmly even if said web be thicker at one margin than at the opposite margin due to the fan-folding of the web. Effective upon the individually pressed clamps, there are provided means whereby said clamps may be shifted to release the record-web and conversely shift it oppositely to grip said web, said means being operable between two positions, one position determining the gripping of the clamps and the other position determining the release of the clamps. To release the record-web the clamps need only be withdrawn a short distance from the paper-table against which they clamp said webs, and said clamp-controlling means are arranged accordingly. It is further contrived, according to the present invention, to withdraw the clamps farther than their normal web-releasing positions in order to be able to freely manipulate said web, and this without disturbing said clamp engaging and disengaging means so that, irrespective of whether said means are conditioned to release or engage said clamps, said means will maintain said condition when the clamps are moved beyond their normal ineffective positions to tear off or adjust the record-web so that after such manipulation of the record-web the clamps will reassume, as before, either their web-releasing or web-engaging condition. The clamps may be moved up a short distance by a handle prior to line-spacing, but when it is desired to tear off the record-web these clamps are swung up a sufficient distance to enable an operator to pull the web forward and tear it off.

The upper group of blades holds carbons interleaved between plies of a multiple-ply record-web, each ply bearing a succession of day-book-forms, and the web-plies extending out at each side beyond the side edges of the interleaved carbons to form margins which the clamps may grip and still leave said carbons free to be retracted. The record-web also extends beyond each side of the statement-web which is also interleaved with carbons held by the lower group of blades. In loading the machine with the two multiple-ply webs, the leading edges of the carbon-sheets of both webs are evened to within a short distance of the cut-off knife, the platen having been raised to its usual loading position and said knife being below the printing line. The platen is then lowered, and both webs with their leading edges about even are

rolled forwardly together around the platen until the first writing line of the leading form of the day-book-web is disposed at the printing line which will bring the leading end of the record-web under the aforesaid clamps which are disposed accordingly and are latched in ineffective positions. The web-clamping means of the present invention are an improvement over those shown in the patent to Alfred G. F. Kurowski, No. 1,642,248. After making the clamps effective against the side margins of the record-web and raising the platen again, the carbons for both webs are stripped, the leading set of statement-forms being at the same time gripped by the operator and advanced to the aforesaid gage-bar. Said statement-forms may be then cut off and wasted, which leaves the first line of writing of the next set of forms at the printing line, both webs now being in position for the first typing operation which may be begun after lowering the platen and releasing the clamps. After typing the two sets of superposed statement-forms and day-book-forms and line-spacing both forms, the clamps are lowered again to effective position, and, because of being laterally disposed for gripping the side edges of the record-web-plies, so as to clear the narrower interleaved carbon-sheets of the record-web, the latter may be stripped rearwardly by the same movement of the carbon-carrier which strips the carbons from the typed set of statement-forms, the latter set of typed statement-forms being at the same time drawn forward, gaged, and then cut off when the platen is lowered. As far as the day-book-form alone is concerned, it is of course not necessary to retract the carbons interleaved therewith every time the carbons for the statement-form are retracted. It is, however, no disadvantage to do so. On the contrary, to simultaneously retract the carbons for both forms makes it possible to employ only one carbon-carrier, and this constitutes an important feature of the invention, conducing to simplicity of the organization. Lateral guides are provided for the statement-web, and include flanged bar-members which may be mounted on the aforesaid cut-off-gage cross-shaft above the delivery side of the platen in such way as to be normally disposed substantially parallel to the paper-table just above the record-web. Means are provided for swinging the statement-web lateral guides upwardly so as to permit a set of typed day-book-sheet-forms to be drawn forward and severed. Said statement-web lateral guides and paper-table thus form a web-course for the record-web. To cut off a condensed record day-book-form after typing the last line thereon, it and the overlying statement-form are rolled forward until the usual perforated dividing line at the bottom of the day-book-form aligns

- with the knife, the typed statement-form being disregarded until the day-book-form is severed. The side edge clamps are now made effective, the platen raised, and the carbons 5 of both webs retracted, after which the platen is lowered. The lateral statement-web-guides are now swung up and the clamps swung forward and the typed day-book-form may now be conveniently pulled forward and 10 severed along the weakened perforated line at the knife without injury to the statement-form. Both webs are now rolled upward to bring the leading edge of the next day-book-form under the clamps and its first line of 15 writing at the printing line. The clamps may now be lowered, the platen raised, and the typed statement-forms pulled forward, gaged, and then cut-off when the platen is lowered again. The leading forms of both 20 webs are now in position to have the next line of statement-data typed on them.

Since it is usual to type but one line on the small statement-form, only a short portion of each typed set of statement-forms, after 25 the usual condensed record line-spacing, will project up from the cut-off knife, to be grasped by the operative and pulled ahead to the cut-off gage. It is a feature of the present invention to provide conveniently positioned means for swinging the cut-off knife downwardly to expose more of the typed statement-form so that it may be conveniently grasped by the operative.

It is another feature of the present invention to provide means for swinging both of the record-web-gripping clamps forwardly as a unit a much greater distance than is provided for in the above-noted patent to Kurovski, to enable the clamps to be moved out 40 of the way of a typed record-web-form so that it may be conveniently drawn forward and severed.

Another feature of the invention resides in the organization of certain elements, including the record-web-plies, the record-web-carbons, the record-web side-edge gages, and the side-edge clamps, so that the carbons may be stripped from the record-web without requiring any gripping of the record-web by the operative's hands.

Still another feature is the provision of clamping devices which will urge each of the two side-edge clamps against the platen independently of the other to assure positive 55 gripping engagement of both clamps.

Other features and advantages will herein-after appear.

In the accompanying drawings,

Figure 1 is a fragmentary sectional view, 60 front to rear, of an Underwood continuous-billing bookkeeping typewriting machine, having my invention applied thereto.

Figure 2 is a diagrammatic view, illustrating how a multiple-ply statement-web 65 and an underlying multiple-ply record-web

are positioned after the first line of data is typed on the leading form of the statement-web and the latter is line-spaced ahead for condensed record-work.

Figure 3 is a diagrammatic view, illustrating certain operations required preparatory to straightening out the statement-web and gaging its leading form to cutting-off position. 70

Figure 4 is a diagrammatic view, showing 75 the platen displaced upwardly and the carbons stripped from the record-web and statement-web, and the leading form of the latter gaged to cut-off position.

Figure 5 is a diagrammatic view, illustrating 80 a method of severing a typed set of forms of the statement-web, while leaving the record-web clamped in place in the machine. A dot-and-dash representation of the record-web in this view illustrates a way of severing 85 the clamped record-web along a perforated line between two forms.

Figure 6 is a diagrammatic view, illustrating 90 a method of severing a typed form of the record-web by means of the cut-off knife.

Figure 7 is a partial diagrammatic plan view of the machine shown in Figure 5, illustrating 95 how the side-edge clamps may grip the record-web and leave the interleaved carbon-sheets free to be stripped upon displacing the platen.

Figure 8 is a fragmentary front perspective view of the carriage of the typewriting machine shown in Figure 1.

Figure 9 is a detail view of a yielding detent-device for holding a gage-carrying cross-shaft in effective position. 100

Figure 10 is a diagrammatic view of a small statement-form, and a day-book-form much larger than the statement-form, for 105 making a condensed record of a single line of data typed on each statement-form, both the statement and day-book forms being arranged for use in the typewriting machine illustrated in Figure 1.

In an Underwood bookkeeping typewriting machine embodying the Wernery-Smith continuous-billing feature, a type 10 may be swung by instrumentalities, not shown, up against a platen 11 having a shaft 12 journaled in a platen-displacing frame 13 pivotally mounted in forwardly-extending members 14 of a carriage 15. Instrumentalities, not shown, disposed adjacent the left end of the platen, may be employed for line-spacing the latter forwardly. The platen may be rotated forwardly and rearwardly by means of finger-wheels 16, only one of which is shown adjacent the right end of the platen, which finger-wheel is mounted on a stub-shaft 17, which is journaled in the adjacent side of the carriage-frame and carries a gear 18 arranged to mesh with a wider idle gear 19, the latter being mounted on the carriage 115 for meshing with a gear 20 fast on the end 120

125

Figure 2 is a diagrammatic view, illustrating how a multiple-ply statement-web and an underlying multiple-ply record-web 130

of the platen-shaft 12. A rear paper-table 21 has a forwardly-extending apron 22 arranged with cut-outs through which feed-rolls 23 may protrude to engage against the 5 lower side of the platen 11. A rearwardly-extending track 24 is supported at its forward end by a bracket 24^a fastened to the carriage, and is supported at its rear end on instrumentalities, not shown, for movement laterally with said carriage. The parts described hereinbefore may be substantially 10 the same as those disclosed in the patent to William F. Helmond, No. 1,572,189, dated February 9, 1926.

15 16 A carbon-carrier 25, having a forwardly-extending handle 26, is mounted in a usual way for running on the track 24, and is arranged with a lower forward group 27 and an upper rear group 28 of carbon-holding 20 blades 29. The blades in each group are mounted in the usual stepped relation to each other, and, for a purpose to presently appear, the lowest blade of the upper group 28 is spaced a considerably greater distance 25 above the upper blade of the lowest group 27 than the vertical distance between blades in the same group.

Some stock exchanges require of each 30 stock-broker member a daily condensed record, on sheets of a prescribed size, of certain customer-statements relating to sales of stock. Each of such statements usually consists of one line of data manifolded on a set of small statement-forms. Each stock-broker's office 35 usually requires one or more carbon-copies of each of the condensed record-sheets, sometimes called day-book-sheets, furnished by the office to the stock exchange. To perform this work expeditiously in a typewriting machine embodying the present invention, a 40 multiple-ply record-web 30 may have plies as wide as the above-noted day-book-sheets and may be interleaved with carbon-sheets 31 held by the upper group 28 of the blades 29.

45 46 The carbon-sheets 31 are narrower than the plies of the record-web 30 and each side edge of a carbon-sheet will be spaced inwardly a certain amount from the side edges of the plies of the record-web (Figure 1), as will 50 appear more particularly hereinafter. The record-web-plies may be divided by usual transverse creased or perforated lines 32 into sets of day-book or record forms 33 as long as said day-book-sheets. Each record-section 55 or form 33 may have a suitably printed block heading 34. Each statement will preferably be manifolded on a set of superposed fan-folded printed forms 35 adjacent the top edge thereof (Figure 10), which forms may 60 be joined, end to end, to a succession of like forms and constitute a multiple-ply fan-fold statement-web 36.

65 Carbons 37, held by the lower group 27 of blades 29, may be interleaved between the plies of the statement-web 36. Both the web 30 and the web 36 may be passed forwardly under the platen while the latter is displaced into the Figure 4 position, and the carbons 31 may be evened with the carbons 37 in a well-known way. The leading end of the 70 first form 33 of the record-web 30 will be advanced far enough to be gripped at each side edge by a clamp 40 against a usual paper-table 41 at the delivery side of the platen which will dispose the first line of writing of 75 the form at the printing line. Each of the clamps 40 may include an arm 42 pivoted forwardly from the platen and having an in-reaching tab 43 arranged with friction pads 44, and may be similar to clamps disclosed in 80 the patent to Alfred G. F. Kurowski, No. 1,642,248, dated September 13, 1927. The clamps disclosed in said patent, however, are fastened to a lateral rock-shaft and can only be manipulated by rotating said shaft. In 85 the present invention, each clamp 40 has a hub 45 loosely mounted upon a shaft 46, which is journaled in the forward ends of integral forwardly-extending bracket-members 47 of side plates 48 of the platen-displacing frame 13. A coiled wire-spring 50 is wound around each hub 45 and has one end fastened to a screw 51 in a collar 52, the latter being fastened on the shaft 46 for lateral adjustment by the screw 51. The other end 90 of each spring 50 extends rearwardly alongside the adjacent arm 42 and has a lateral hook-portion 53 engaging in a hole 54 in the arm. Each spring 50 is arranged with an initial tension so that it always tends to urge its 95 associated arm 42 clockwise against the paper-table 41.

Means are provided for urging the shaft 46 in a clockwise direction, including an upwardly-extending arm 55 fast on the right 105 end of the shaft and a tensile spring 56 having one end fastened to the upper end of said arm and the other end to the adjacent side plate 48. Said urging means also include a cam-plate 57 fast on the left end 110 of the shaft 46, a pin 59 in said cam-plate, and a spring 58 having one end fastened to the pin 59 and the other end to a pin 60 in the adjacent side plate 48. The cam-plate 57 extends rearwardly and upwardly and has a tooth 61 which is positioned to engage 115 against a forwardly-protecting heel-like member 62 on the lower portion of an upwardly-extending lever-handle 63, which is pivoted below the heel-member 62 and has a finger-piece 65 at its upper free end. The construction of the arm 55, the cam-plate 57 and the handle 63 may be the same as is disclosed in the above-noted patent to Kurowski. 120

125 I will be seen from an inspection of Figures 1 and 2 and the above-noted patent to Kurowski, that a counterclockwise movement of the handle 63 is effective to move the cam-plate 57 a small amount in the same 130

direction. Both parts are then latched against return movement by the tooth 61 engaging the heel-member 62. To make this movement of the cam-plate effective to raise the work-sheet-gripping tabs 43 away from the paper-table, a rearwardly-extending rock-arm 66 is fastened for lateral adjustment by a screw 67 on the rock-shaft 46 against each arm 42 and on the opposite side from the adjacent collar 52. A laterally-disposed pin 68 is rigidly fastened in the rear end of each arm 66 to lie against the under side of the adjacent arm 42 and swings the latter counterclockwise upon a like movement of the handle 63.

To enable the tabs 43 to be swung a much greater distance forwardly from their effective work-sheet gripping positions than can be done by the handle 63, for a purpose to appear hereinafter, a laterally-disposed rod 69 is loosely fastened between the arms 42 by shoulder-screws 70 which pass through over-size holes 70^a in the arms to be threaded into the ends of the rod and may be easily pulled forwardly against the tension of the springs 50 by an operative's finger, as illustrated in Figure 6. To permit the clamps 40 to be adjusted relatively to each other for use with record-webs of different widths, the rod 69 is made in two sections 71 and 72 which are connected by a sleeve 73, which engages around the inner end portions of each section 71 and 72 and is adjustably fastened hereon by set-screws 74.

It will be noted that the above-described arrangement of the clamps 40 and the clamp-operating mechanism is effective to urge each clamp against the paper-table independently of the other, thereby assuring a positive grip of a work-piece by each of the clamps regardless of small manufacturing variations. It will be further noted that the two independently spring-urged clamps are movable to each of their ineffective positions as a unit.

Employment of the rod 69 permits the tabs 43 to be swung forward out of the way of the record-web 30 when it is desired to pull the latter forward and sever a typed record-form 33 at a knife 75. This knife may include a laterally-disposed blade 76 mounted on two arms 77, each journaled on the platen-shaft 12 at each end of the platen, and having an enlarged portion arranged with a cam-slot 78 in which may engage a pin 79 fast in the lower end of an arm 80, which is fastened on a rock-shaft 81 journaled in the side plates 48 of the platen-displacing frame 13. An upwardly-extending rock-arm 82 is fastened on the rock-shaft 81 adjacent the left end of the platen and terminates in a finger-piece 83. A spring 84, fastened to each of the arms 80, normally holds the pins 79 in the forward ends of the slots 78, which arrangement is effective for

holding the blade 76 in its effective cutting-off position. By pressing the finger-piece 83 forwardly, the blade 76 is swung counterclockwise, as is fully set forth in Patent No. 1,281,087, granted to me October 8, 1918, 70 which patent discloses the construction of a knife substantially like the knife 75 described above, except that the knife-swinging handle is mounted at the right end of the platen, instead of the left, as is done in 75 the present invention for an advantage to appear hereinafter.

The platen 11 is locked down in its typing position by upright locking arms 87, each of which is fastened on a rock-shaft 88. A notch 89 is provided in the forward edge of each of the locking arms 87 and engages about a stud 90 fast in the adjacent side plate 48. The lower edge of the notch 89 is arranged to act as a cam, and is effective to raise the platen a small amount when the shaft 88 is rocked rearwardly by means of a usual finger-piece 91 on an upward handle-extension 92 on the left-hand locking arm 87. The construction of the locking arms 87 and the notch 89 may be the same as is disclosed in my co-pending application, Serial No. 202,631, filed June 30, 1927 (now Patent No. 1,749,550, dated March 4, 1930). 90

The sales data is typed on a statement-form 35 in columns 95 and is required to be copied accurately in columns 96 of a day-book-form. To this end, adjustable lateral guides 97 and 98 for the statement-web and record-web, respectively, may be mounted at 100 the rear of the bracket 24^a and be of the same construction as the lateral web-guides disclosed in my co-pending application, Serial No. 108,451, filed May 12, 1926 (now Patent No. 1,690,844, dated November 6, 1928). To 105 co-operate with the guides 98, there is provided a lateral guide which includes an angle-plate 99 adjustably mounted on the paper-table 41 by means of a lengthwise laterally-disposed slot 100 in a base-portion 99^a of the 110 angle-plate and two set-screws 101. To co-operate with the guides 97, lateral guiding means for the statement-web are provided at the delivery side of the platen and include two plates 102 disposed parallel to the paper-table 41 a short distance above it, each plate having an upturned guide-flange 103 to come at each side of the statement-web. To provide for lateral adjustment of the guide-flanges 103, the upper ends of the plates 102 may be bent or curled closely around a laterally-disposed rock-shaft 104 (Figure 8) having a longitudinal groove 104^a into which groove ridge-like elements 102^a on the curled ends of the plates 102 may be pressed by 115

spring-action of the curled ends. The shaft 104 is supported on the upper ends of two upwardly-extending bars 105, fastened at the rear side of the paper-table 41 by screws 106 passing through lengthwise slots 107 in the 120 125 130

plates and engaging in tapped holes in a usual angle-plate 108 fastened between the side plates 48. Record-data regarding each sale, which it is not desired to have appear on the statement-forms 35, may be typed in a column 96^a on the day-book-forms 33 beyond the side edge of the statement-form.

The plates 102 and their flanges 103 not only guide the statement-web laterally, but 10 also serve to deflect the underlying record-web 30 rearwardly in close contact with the paper-table 41. To assure better deflection of the record-web, an intermediate deflector-plate 109 is mounted on the rock-shaft 104 15 between the plates 102 in the same manner as the last-named plates. The upper edge of the shaft 104 (Figure 4) is employed as a cut-off gage for the statement-web-forms. To deflect the leading edge of the statement-form 20 past the body of the rock-shaft 104 as the form is pulled forward to cut-off position, an integral deflector-finger 109^a may be formed out of the curved rim-portion of the deflector-plate 109, as illustrated in Figure 8.

25 For a purpose to presently appear, it is desirable to swing the plates 102 and 109 upwardly. To this end, each end of the shaft 104 is journaled in a U-shaped bracket 111 fastened on the upper end of the adjacent bar 105, and a crank-arm 112 is fastened to the right end of the shaft 104. Each bracket 111 forms part of a detent-device of 30 a construction well-known in the typewriter art. This device includes a roller 113 pressed against the shaft by a leaf-spring 114. A short lengthwise groove 115 is provided in each end of the shaft 104 and is positioned so that, when the plates 102 and the plate 109 35 are disposed parallel to the paper-table 41, the rollers 113 engage in the grooves 115 and hold the plates in their normal effective positions.

The operation of the typewriting machine embodying the present invention for preparing the above-noted multiple statement-slips and a multiple condensed record thereof may be as follows: Carbon-sheets 31 for each web may be fastened to the proper blades 29 so that the free ends of all the carbons 40 will be evened when the blades are mounted on usual stepped blocks 116 and the carbons interleaved between the plies of the webs and extended forwardly toward the platen. The carbons between the record-web-plies are 45 preferably spaced inwardly from the side edges of the latter a distance one-half an inch or more in excess of the width of the rubber friction-pads 44. The platen being displaced to web-straightening position as in Figure 4, 50 both webs are passed forwardly between the knife 75 and the platen 11, and the leading edge of the record-web gripped at the side margins of said record-web by the clamps 40, which will position the first line of writing 55 of the leading day-book-form at the print-

ing line. The leading edge of the statement-web 36 may be gripped by the operator's one hand and the carbon-carrier 25 moved rearwardly by the other hand far enough to bring the leading ends of the carbons about one-half 70 an inch to the rear of the cutting edge of the knife, and a stop-pin 117 will be placed on the track 24 behind the carbon-carrier so as to arrest its rearward movement at that point thereafter, and thus gage the leading edges 75 of the carbons to fall short of said knife. While the carbon-carrier is held against the pin 117, the leading end of the first set of statement-forms will now be pulled ahead to the cutting-off gage, the platen restored, and the first set of forms cut off and wasted. It will be understood that instead of merely holding the statement-web 36 while the carbon-carrier 25 is shifted backwardly, said statement-web 36 may, concomitantly with 80 the rearward shift of said carbon-carrier, be advanced to said cutting-off gage. The side-edge clamps 40 are now raised and latched in their ineffective position by operation of the finger-piece 65, leaving the first lines of writing 85 on the leading statement-form and the leading day-book-form at the printing line, both webs being held closely against the platen at the printing line by usual sheet-pressers or guards (not shown).

The usual one line of data may now be typed on the original statement-form and carbon-copied on the underlying forms of both webs, after which both forms are line-spaced ahead an amount which will provide the desired condensed record-spacing on the day-book-forms. The side-edge clamps are lowered to effective position by pressing rearwardly on the finger-piece 65 preparatory to stripping the carbon from the typed statement-form. Since only one line is usually typed on a small statement-form 35, the subsequent condensed-record line-spacing of the form is usually insufficient to advance the leading edge of the typed statement-form far enough above the sharp cutting edge of the knife-blade 76 to afford a convenient and secure grip on the form by the operative's fingers. It is desirable, therefore, for the operative to swing the knife-blade down by 110 pressing the finger-piece 83 forward with one finger of her left hand, which can be done while another finger of the same hand is used to unlatch and slightly raise the platen 11 by 115 pressing rearwardly on the finger-piece 91. The operative is thus enabled to grasp the top of the typed form with her right hand and pull both the web-plies and carbons slightly 120 ahead to secure her grasp. Then, with her left hand, the operative will swing the platen 125 upward to its displaced position, push the carbon-carrier to the rear, and draw the leading edges of the typed set of statement-forms to the cutting-off gage with her right hand. Because of the clamps 40 being positioned 130

for gripping the side edges of the record-web-plies far enough outwardly from the side edges of the carbon-sheets interleaved between the plies, the record-web carbon-sheets 5 may be stripped rearwardly by the same operation that strips the carbon-sheets of the outer statement-web even though two or more lines be typed on a statement-form and the leading edges of the interleaved carbons advanced considerably beyond the clamps. 10 After lowering the platen, the typed statement-form may be cut off, the side-edge clamps released, and the succeeding form typed and cut off in the same manner as described above. 15

When the last line of data has been typed on a set of day-book-forms of the record-web, the latter and the statement-form-web are rolled forwardly until the perforated dividing line at the bottom of the typed day-book-form is aligned with the cutting edge of the blade 76. The typed statement-form may be disregarded for a time until the typed day-book-form is severed. The clamps 40 25 are lowered to effective position, the platen displaced, and the carbons of both webs retracted below the blade 76, after which the platen is lowered. The deflector-plates 102, 109 are now swung up and the clamps 40 30 swung forward as a unit to the Figure 6 position, and the typed set of day-book-forms may now be conveniently pulled forward and severed along the weakened perforated lines at the position of the knife, which severing 35 operation can be performed without injury to the statement-form interposed between the day-book-form and the knife. The deflector-plates 102, 109 may now be swung down to normal position, and the clamps 40 lowered 40 to their ineffective positions, and both webs rolled up sufficiently to bring the leading edge of the next day-book-form under the clamps and the first line of writing of the form at the printing line. The clamps may 45 now be lowered to effective position, the platen raised, the carbons stripped, the typed statement-form pulled forward, gaged and cut off, and the platen is lowered. The leading forms of both webs are now in position 50 for being typed with the next line of statement-data.

A typed day-book-form may also be severed by a different method from that described above. After writing the last line on the day-book-form, both the latter and the statement-form are rolled up together until the top edge of the next day-book-form is under the line of the forward sides of the pads 44. The clamps are lowered to effective 55 position, the platen raised, the carbons stripped, and the typed set of statement-forms gaged to cut-off position, after which the platen may be lowered and the statement-forms cut off by the knife. The deflector- 60 plates 102, 109 may now be swung upwardly 65

and the typed day-book-form torn off along the perforated line at the clamps. The clamps may now be raised and both webs are left in position for the next typing operation. 70

Worn portions of the carbon-sheets used with the statement and record webs may be conveniently severed in the following manner. After typing the last line on the leading day-book-form, the stop-pin 117 will be advanced a distance equal to the depth of the carbon-sheets that it is desired to tear off. Both webs are next rolled forward to position the perforated line at the bottom of the typed day-book-form under the line of the forward sides of the pads 44. The clamps are 75 now lowered, the platen raised, and the carbon-carrier moved rearwardly to within about one-half inch of the stop-pin 117. The leading edge of the statement-form will now be pulled forward to the cut-off race, the platen lowered, and the typed set of statement-forms cut off at the knife, which operation will also cut off the interleaved statement-web-carbons an amount equal to the distance the stop-pin 117 was moved forward. 80 The deflector-plates will next be swung up and the clamps 40 pulled forwardly as a unit to the Figure 6 position, after which both webs will be rolled back to bring the perforated line at the bottom of the day-book-form to align with the cutting edge of the knife. The typed set of day-book-forms will 85 now be severed along the perforated line by drawing it across the knife, which operation will also sever the interleaved carbons when they extend above the perforated line. In some cases, where the stop-pin 117 has been advanced only a short distance, the worn portions of the record-web-carbon-sheets 90 will not extend above the perforated line at the bottom of the leading day-book-form upon carrying out the above-noted operations, and, therefore, will not be severed with the typed set of day-book-forms. The worn carbon-portions will, however, be advanced 95 above the printing field and will be in position to be subsequently severed when the stop-pin 117 is advanced again for severing typed portions of the statement-web-carbons. After cutting off the day-book-form, the clamps 100 may be lowered to their ineffective positions and the deflector-plates swung downwardly to normal position, and both webs may be rolled forward sufficiently to bring the leading edge of the next day-book-form in position to be gripped by the clamps 40, which 105 will bring the top of the next statement-form at the knife, and the first lines of writing of the statement-form and day-book-form 110 will be disposed at the printing line ready for the next typing operation. 115

It can readily be seen by those skilled in the art that the statement-webs and record-webs may be manipulated in a different man- 120 125 130

ner from the present disclosure without departing from the scope of my invention.

The operation of the machine is as follows:

The day-book fan-fold web-forms together with the statement fan-fold web-slips are fed from the rear of the machine over a single carbon-carrier having carbons mounted thereon and interleaved between both sets of webs. The webs together with the carbons are inserted in the machine around the platen and fed up far enough to permit clamps at the front of the machine to grip the side edges of the day-book-web, which simultaneously positions this web for the first line of typing. The clamps are then moved to effective position to hold the day-book-web stationary while the platen is displaced and the statement-web pulled up to an aligning gage. The carbons are then retracted, and, due to the carbons not extending out to the edges of the day-book-web, the clamps do not grip them and allow them to slip through the day-book-forms while the latter are held stationary. The platen is then lowered to its normal position and the gaged statement-web is torn off and wasted. The clamps are then released and the first line typed, after which the webs are line-spaced. The operator is now ready to strip the first set of typed statement-slips while the day-book-web remains stationary. However, the statement-slips have only been line-spaced once and the distance that they were fed above the cutting-off knife is not sufficient to enable the operator to obtain a good grip to pull them forward. To accomplish this, the knife is displaced by means of a handle mounted near the day-book clamp-handle and also near the swingable platen-frame locking-lever-handle, so that the operator may now, with one hand, move the knife down, move the clamp to hold the record-web stationary, and release the platen-displacing, locking lever, while the other hand grips the statement-web and lifts the platen-frame to displace the platen. The statement-web is then pulled up to the gage and the carbon-carrier retracted to strip the carbons from both webs. The platen is now lowered to its normal position and the statement-web severed, the clamps released, and the operator is ready for typing the next line.

For tearing off the day-book fan-fold forms, the operation is as follows:

After having typed a statement-form together with the last line on the day-book-form, the forms are fed up by means of rotating the platen until the perforated lines on the day-book-form align with the top edge of the severing knife (nothing being done with the statement-form until after the typed day-book-forms are severed and the new forms positioned). The clamps are now moved to effective position, the platen is displaced and the carbons retracted, after

which the platen is lowered to its normal position, and the lateral statement-gages swung up to permit the day-book-forms to be pulled out, and then the clamps are swung forward, to the position of Figure 6, to enable the forms to be severed along the perforated line against an edge of the statement-forms which rest on the top edge of the knife. The webs are then fed up by rotation of the platen until the leading edge of the day-book-web comes underneath the clamps, which simultaneously positions the day-book-form to its first line of typing. The clamps are then moved to effective position, the platen displaced, and the typed statement-slips pulled forward to the gage and the carbons stripped therefrom, after which the platen is swung down to its normal position and the statement-slips severed. The webs are then in position for receiving the next typing operation.

Variations may be resorted to within the scope of the invention, and portions of the improvements may be used without others.

Having thus described my invention, I claim:

1. In a web-manifolding typewriting machine having means for interleaving carbons between the fan-fold plies of the web, a traveling carrier, a displaceable frame on the carrier and having a platen provided with web-feeding means by which the web and carbons are fed around the platen, the machine being adapted for carrying simultaneously a wide web and a superposed narrow web, and a pair of carbon-packs spaced apart from each other, one pack of carbons interleaved with the plies of the wide web and the other pack of carbons interleaving the plies of the narrow web, with the wide web and its carbons feedable next to the platen and the narrow web feedable over the wide web, the combination of paper-tables supported by said displaceable frame at the delivery side of the platen, one table for each web, a pair of clamps pivotally hung from said displaceable frame and effective to clamp the two edges of the wide web to its table while the narrow web and its carbons are adjusted to the wide web and to the typing position of the platen, means for shifting said clamps to and from effective web-clamping positions, a web-severing blade supported from each end of the displaceable frame and effective to sever one web without severing the other web, frame-locking-down means for holding the platen in typing and web-feeding position, a web-releasing lever at one end of said carrier and effective to raise the displaceable frame and disable the web-feeding means, and means mounted upon the displaceable frame and adjacent the web-releasing lever, whereby the fingers of the same hand may jointly release the web-feeding means and lower the position of the web.

severing blade to provide a grip for the fingers of the other hand at the leading-in end of the narrow web to draw the narrow web around the clamped wide web to a severing position on said narrow web.

2. In a device of the class described having a platen around which may be fed a record-web, a paper-table at the delivery side of said platen, a platen-displacing frame supporting said platen and said paper-table, and a cut-off knife, the combination with said knife of a cut-off gage supported on said frame, including two upwardly-extending arms mounted for up-and-down adjustment, one arm at each side of said table, a cross-shaft mounted between the upper ends of said arms and constituting said cut-off gage and two downwardly-extending side edge guides supported by said shaft for a statement-web narrower than said record-web and overlying the latter, said shaft rockable for swinging said side edge guides away from said record-web to permit the latter to be drawn forward and a section thereof cut off by said knife.

25 3. In a web-manifolding carbon-stripping typewriting machine, in combination, a platen around which may be fed a multiple-ply record-web divided into sets of day-book forms and interleaved with carbons, and an overlying multiple-ply form-bearing statement-web interleaved with carbons, a collating table for each web, a gaging knife for cutting off a typed form from either web, means including a finger-piece operable by one hand for displacing said knife downwardly to enable the other hand to securely grip the exposed leading edge of said statement-web after a single line has been typed thereon and line-spaced with the condensed-40 record web, a cutting-off gage for the leading edge of said statement-web, and clamping means normally disengaged and including a finger-piece operable to clamp said record-web to its collating table while the typed form 45 of the statement-web is advanced by one hand to said cutting-off gage, said clamping means arranged so that the operating finger-piece thereof is adjacent the finger-piece of the knife-displacing means for concomitant control of said finger-pieces by the other hand.

4. In a device of the class described, having a platen-displacing frame, a platen in said frame around which may be fed a multiple-ply work-web interleaved with carbons 55 and a paper-table supported on said frame at the delivery side of said platen, the combination with a cut-off knife for said web carried by said frame, and side-edge guides for said work-web at the delivery side of said platen above said knife, of a cut-off gage for said work-web including two upwardly-extending arms adjustably supported on said frame, and a cross-member against which said web is gaged, said cross-member supported on the upper ends of said arms,

said side-edge guides being fastened on said cross-member and extending downwardly therefrom toward said platen.

5. In a device of the class described, having a platen-displacing frame, a platen in said frame around which may be fed a multiple-ply statement-web and a wider underlying multiple-ply record-web, both webs being interleaved with carbons, a paper-table supported on said frame at the delivery side of said platen, the combination with a cut-off knife carried by said frame, of a side-edge guide positioned on each side of the narrower statement-web at the delivery side of said platen, a cut-off gage for said statement-web including two upwardly-extending arms supported on said frame and a cross-member against which said statement-web is gaged, said cross-member supported on the upper ends of said arms, said side-edge guides being fastened on said cross-member and extending downwardly therefrom toward said platen parallel to said paper-table in close proximity to said record-web, and means for swinging said cross-member to swing said guides upwardly to permit said record-web to be drawn forward and severed on said knife.

6. In a device of the class described, a platen-displacing frame, a platen in said frame around which a work-web may be fed, a paper-table at the delivery side of said platen supported on said frame, a rock-shaft mounted in said frame forwardly from said platen and extending lengthwise of the latter, clamps mounted on said rock-shaft for clamping said work-web against the paper-table, means including a finger-piece, cooperating with said rock-shaft for raising said clamps to ineffective positions a short distance above said table, and devices for swinging said clamps forwardly, as a unit, a much greater distance from said table than said raising means is effective to do and without displacing said raising means or rock-shaft.

7. In a device of the class described, a platen-displacing frame, a platen in said frame around which may be fed a work-web, a paper-table at the delivery side of said platen supported on said frame, a rock-shaft mounted in said frame forwardly from said platen and extending lengthwise of the latter, clamps mounted on said rock-shaft for clamping said work-web against the paper-table means, including a finger-piece, cooperating with said rock-shaft for raising said clamps, as a unit, a short distance above said table, devices for raising said clamps, as a unit, a much greater distance than said raising means is effective to do and without displacing said raising means or rock-shaft and instrumentalities for urging each of said clamps independently of the other against said paper-table.

8. The device described in claim 6, having means for automatically latching said clamps in the first-reached ineffective position.

9. In a web-manifolding, carbon-stripping typewriting machine, the combination with a displaceable platen around which may be fed a multiple-ply statement-web and an underlying multiple-ply record-web wider than the statement-web and extending out on each side thereof, both webs being interleaved with carbon-sheets, said record-web carbons being narrower than said record-web and wider than said statement-web, of means for stripping said carbon-sheets from typed sections of both webs at one operation, said means including, in combination, a single carbon-carrier having blades in spaced-apart groups, said statement-web carbon-sheets fastened to one group and said record-web carbon-sheets fastened to the other group of blades, said latter carbon-sheets being narrower than said record-web so that their side edges are spaced inwardly from the side edges of said record-web, a separate table for each web at the delivery side of the platen, separate lateral guides for each of said webs upon each table, and clamps arranged for clamping said record-web against one table above said platen and away from the side edges of the record-web carbon-sheets, whereby said carbons are free to be stripped from the clamped record-web with the carbons of said statement-web upon displacing the platen and moving said carbon-carrier rearwardly while said statement-web is grasped by the hand.

10. In a typewriting machine of the class described, the combination with a platen-displacing frame, a platen in said frame around which a work-web may be fed, and a paper-table at the delivery side of said platen, of clamp-arms for said work-web, means on which said clamp-arms are fulcrumed independently of one another to swing from and toward said frame and whereby said clamp-arms are spaced to engage the sides of said work-web, means effective for urging each of said clamps against said table independently of the other, and connecting devices between said clamps for moving them to and from their effective positions as a unit.

11. In a continuous billing front-strike typewriting machine having a platen around which may be fed a multiple-ply statement-web and a wider multiple-ply record-web which projects out on both sides from said statement-web, and a cutting-off knife for said webs at the front of said platen, the combination with a paper-table at the delivery side of said platen, of a rock-shaft supported above and crosswise of said table to be effective for gaging said statement-web to cutting-off position, deflector-plates for said record-web having their upper ends attached

to said rock-shaft for lateral adjustment therewith, without turning on said shaft, said deflector-plates extending downwardly parallel to said table and closely adjacent thereto, integral upturned guide-flanges on 70 said deflector-plates arranged to engage the side edges of said statement-web, and a handle on said rock-shaft to rotate the latter for swinging said deflector-plates upwardly out of the way of said record-web to permit 75 typed sections of said record-web to be drawn forward and severed by said knife.

12. In a continuous-billing typewriting machine having a platen around which a record-web which is divided into relatively long 80 form-sections may be fed, and a cutting-off knife, the combination with a paper-table at the delivery side of said platen, of plates for deflecting a typed section of said web rearwardly over said table, said plates also effective 85 to support an overlying statement-web clear of said record-web, a rock-shaft supported above and crosswise of said table and having said plates fastened thereto so as to be disposed parallel to said table, and a handle for revolving said shaft to swing said plates upwardly to permit said record-web to be drawn forward and cut off by said knife.

13. In a web-manifolding typewriting machine having a platen-displacing frame, a platen around which a work-web may be fed and a cutting-off knife for said web disposed forwardly from said platen, the combination with a paper-table mounted on said frame at 100 the delivery side of said platen, of two spring-urged clamp-arms pivotally supported on said frame for gripping the side edges of said work-web against said table, and means connecting said clamp-arms at points spaced 105 from their pivots for swinging said clamp-arms forwardly as a unit a sufficient distance out of the way of said work-web to permit a typed section thereof to be conveniently drawn forward and severed across said knife, 110 said connecting means engaging said clamp-arms loosely so that each clamp-arm may grip independently of the other.

14. In a web-manifolding typewriting machine having a platen-displacing frame, a 115 platen around which a work-web may be fed and a cutting-off knife for said web disposed forwardly from said platen, the combination with a paper-table mounted on said frame at the delivery side of said platen, of a set of 120 two laterally-adjustable, pivotally-mounted clamp-arms supported on said frame for gripping the side edges of said work-web against said table, and means for swinging said clamp-arms forwardly a sufficient distance out of the way of said work-web to permit a typed section thereof to be conveniently drawn forward and severed across said knife, said means including a cross-rod extending 125 between said clamp-arms and spaced from 130

the pivots of said clamp-arms, and devices for adjusting the length of said rod, said cross-rod engaging said clamp-arms loosely so that each clamp-arm may grip independently of the other.

15. In a web-manifolding typewriting machine having a platen-displacing frame, a platen around which a work-web may be fed and a cutting-off knife for said web disposed forwardly of said platen, the combination with a paper-table at the delivery side of said platen, of a web-clamping device including a rock-shaft mounted in said frame forwardly from said platen, clamp-arms loosely mounted on said rock shaft for gripping said work-web against said table, means for rotating said shaft between two positions and holding it in either position, and whereby in one position said rock-shaft holds said clamp-arms clear of said table and in the other position permits said clamp-arms to grip, mechanism effective for swinging said clamps as a unit around said shaft away from said table without disturbing the position of said shaft, and means effective for urging each of said clamps against said table independently of the other.

16. In a web-manifolding typewriting machine having a platen-displacing frame, a platen around which a work-web may be fed and a cutting-off knife for said web disposed forwardly of said platen, the combination with a paper-table at the delivery side of said platen, of a web-clamping device including a lateral rock-shaft mounted in said frame forwardly from said platen, a cam-bearing arm fast on said shaft, a lever arm pivoted on said frame and co-operating with a cam on said first-named arm for rotating said shaft between two positions and holding said shaft in either position, clamp-arms loosely mounted on said rock-shaft for gripping said work-web against said table, arms on said shaft whereby the latter in swinging between said two positions swings said clamps as a unit with said shaft away from said table to ineffective positions, means effective for urging each of said clamp-arms against said table independently of the other, and instrumentalities for swinging both of said clamp-arms forwardly, as a unit, from either effective or ineffective position for cutting off said web on said knife.

17. In a web-manifolding typewriting machine having a platen-displacing frame, a platen around which a work-web may be fed and a cutting-off knife for said web disposed forwardly of said platen, the combination with a paper-table at the delivery side of said platen, of a web-clamping device including a lateral rock-shaft mounted in said frame forwardly from said platen, a cam-bearing arm fast on said shaft, a lever-arm pivoted on said frame and co-operating with a cam on said first-named arm for rotating said shaft between two positions and holding said shaft in either position, clamp-arms loosely

mounted on said rock-shaft for gripping said work-web against said table, arms on said shaft whereby the latter in swinging between said two positions swings said clamp-arms as a unit with said shaft to ineffective positions, means effective for urging each of said clamp arms against said table independently of the other, and connecting devices for swinging both of said clamp-arms forwardly, as a unit, from said ineffective positions, said devices including a rod extending between said clamp-arms and means for fastening said rod loosely to said clamp-arms, whereby the engagement of said rod with said clamp-arms will permit each clamp-arm to be urged independently of the other against the table.

18. In a web-manifolding, carbon-stripping typewriting machine having a platen around which a work-web interleaved with carbons may be passed and a paper-table at the delivery side of said platen, in combination a set of two clamps, each mounted for gripping the side edge of said work-web against said table, two spring devices, each arranged with initial tension to urge one of said clamps towards said table, spring-operated means effective for maintaining the initial tension of said spring devices and devices for moving said clamps to ineffective positions as a unit.

19. In a web-manifolding, carbon-stripping typewriting machine having a platen around which a work-web interleaved with carbons may be passed and a cutting-off knife for said carbons at the delivery side of said platen, the combination of a paper-table at the delivery side of said platen, two clamp-arms individually spring-pressed and individually pivoted forwardly from said platen for gripping the side edges of said work-web against said table, manual means effective for swinging and locking said clamp-arms, as a unit, in ineffective positions adjacent said paper-table, means for manually swinging both clamp-arms together from said table a greater distance than to the clamp-arm-locking position, to permit the typed section of said work-web to be conveniently severed across said knife, and means for restoring said clamp-arms, after either manual operation, to bear against said paper-table.

20. The structure described in claim 19, in which the means for swinging both clamp-arms a greater distance than the clamp-arm-locking position is a rod having connections with both clamp-arms, so that the clamp-arms may be independently urged against said paper-table.

21. In a continuous billing typewriting machine having a platen around which superposed multiple-ply work-webs may be passed, and a cutting-off knife for said webs, the combination with a gaging device for the outer web including a cross-shaft supported above said knife to serve as a cutting-off gage for

- 5 said outer web, and side-edge guides for said outer web, consisting of two plates which have their upper ends fastened to said shaft, and which extend downwardly therefrom toward said platen and have upwardly-extending integral flanges for engaging the side edges of said outer web, of a paper-table spaced from said plates to form a web-course for the inner web.
- 10 22. In a continuous billing typewriting machine having a platen around which may be fed two work-webs of different widths, the narrower web overlying the other, a cutting-off knife, and a paper-table at the delivery side of said platen above said knife, means for supporting said narrower web slightly above said table clear of the wider web, said means including a cross-shaft supported above said paper-table, and plates on said 15 shaft extending downwardly parallel with said table, said plates being swingable upwardly to be removed from the path of the wider work-web when the latter is drawn forward to be severed by said knife.
- 15 23. The device described in claim 22, characterized by means for fastening said plates on said cross-shaft for lateral adjustment therealong, said means including a lengthwise groove in said cross-shaft, curled portions having initial spring tension arranged 20 on said plates for gripping said cross-shaft by spring-action, and in reaching ridge-like elements in said curled portions arranged for interlocking with said groove, and held 25 therein by said spring tension.
- 20 24. In a typewriting machine having a platen around which a work-web may be fed, in combination, a paper-table at the delivery side of said platen, a rock-shaft disposed forwardly and lengthwise of said platen, two 25 clamp-arms pivoted loosely on said shaft and extending rearwardly therefrom to grip said work-web against said paper-table, a spring connection between said rock-shaft and each 30 of said clamp-arms effective for urging the latter towards said table, a connection between said rock-shaft and each of said arms effective, by the rotation of said shaft, for moving said clamp-arms away from said 35 table to ineffective positions, and means, including a finger-piece, for rotating said shaft between two positions and holding it in either position, so that in one position said clamp-arms bear on said table, and in the other position are withdrawn from said table, said means arranged to operate by the mere shift of said finger-piece.
- 35 25. In a typewriting machine having a platen around which a work-web may be fed, in combination, a paper-table at the delivery side of said platen, a rock-shaft disposed forwardly and lengthwise of said platen, two 40 clamp-arms pivoted loosely on said shaft and extending rearwardly therefrom to grip said work-web against said paper-table, spring 45 connection between said rock-shaft and each of said clamp-arms effective for urging the latter towards said table, a connection between said rock-shaft and each of said arms effective for urging the latter towards said table, a connecting member between said clamp-arms for 50 withdrawing the latter from said table by rotating said shaft to a clamp-withdrawing position, said shaft-arms being further arranged to recede from said clamp-arms, by rotating said shaft oppositely to a clamp-engaging position in which said spring-connection 55 causes said clamp-arms to bear on said table, and means cooperating with the shaft-rotating spring devices for rotating said shaft between said positions and holding it in either 60 position.
- 55 26. In a typewriting machine having a platen around which a work-web may be fed, in combination, a paper-table at the delivery side of said platen, a rock-shaft disposed forwardly and lengthwise of said platen, two 65 clamp-arms pivoted loosely on said shaft and extending rearwardly therefrom to grip the side edges of said work-web against said paper-table, a spring-pressed arm fast to said shaft for urging said shaft to rotate in a direction to swing said clamp-arms toward said table, two springs coiled around said shaft, one adjacent each of said clamp-arms for connecting the latter and said rock-shaft, said coiled springs urging said clamp-arms 70 toward said table, a connection between said rock-shaft and each of said clamp-arms effective, by the rotation of said shaft, for moving said clamp-arms from said table, a camming and latching member opposing said spring-pressed arm and co-operating therewith to rotate said shaft between two positions in which respectively said clamp-arms bear upon, and are withdrawn from, said table, and to hold said shaft in either position, and 75 means for swinging both of said clamp-arms together beyond their ineffective position as determined by said camming and latching member against the tension of said coil springs.
- 80 27. In a typewriting machine having a platen around which a work-web may be fed, in combination, a paper-table at the delivery side of said platen, a rock-shaft disposed forwardly and lengthwise of said platen, two 85 clamp-arms pivoted loosely on said shaft and extending rearwardly therefrom to grip said work-web against said paper-table, a spring-pressed arm connected to said shaft for urging said shaft to rotate in a direction to swing said clamp-arms toward said table, a spring connection between said rock-shaft and each of said clamp-arms effective for urging the latter towards said table, a connecting member between said clamp-arms for 90 withdrawing the latter from said table by rotating said shaft to a clamp-withdrawing position, said shaft-arms being further arranged to recede from said clamp-arms, by rotating said shaft oppositely to a clamp-engaging position in which said spring-connection 95 causes said clamp-arms to bear on said table, and means cooperating with the shaft-rotating spring devices for rotating said shaft between said positions and holding it in either 100 position.

swinging the latter together as a unit, means co-operating with said spring-pressed arm for rotating said shaft between two positions, and latching it in either position, and means on said shaft whereby in one position said 5 clamp-arms grip, and in the other position are withdrawn to ineffective positions.

28. In a device of the class described, in combination, a displaceable frame having a 10 platen around which a multiple-ply work-web interleaved with carbons may be fed, means for holding carbons narrower than said web so that the side edges of the plies of said work-web are carbonless, a paper-table secured to said frame and disposed at the delivery side of said platen and displaceable therewith, two clamps pivotally mounted upon said frame and adjustable for different web-widths and disposed forwardly of 15 said paper-table, each clamp effective for clamping the carbonless side edge of said work-web against said table, means for stripping said interleaved carbons from the web and between the clamps, said clamps having 20 means to exert clamping pressure independently of one another, and means for simultaneously engaging or disengaging both clamps from the edges of the web.

29. In a device of the class described having 30 a displacing frame having a platen around which a record-web and a multiple-ply statement-web interleaved with carbons and bearing a succession of sets of forms may be fed, and a web-delivering table the combination of 35 a web-course, supported on said frame, above said table, at the delivery side of said platen, for conducting carbonless typed web-forms away from said platen, a knife carried by said frame and operable to sever typed forms 40 from either web, and a gage for said statement-web including a bar supported between two upwardly-extending arms secured to said frame for up-and-down adjustments for said bar, the leading edge of the web being 45 squared by said bar before the typed form is severed.

30. In a multiple-ply-web-manifolding typewriting machine, the combination with a revoluble platen, of means for presenting to 50 said platen and feeding therearound two superposed multiple-ply work-webs, each bearing a succession of forms, a paper-table adjacent the delivery side of said platen, a web-collating structure including a plurality 55 of web-separating and web-guiding plates over said table and forming therewith a chute for the multiple-ply web that is nearest to said platen, and means supporting said structure and manually rockable for displacing said 60 plurality of plates to thereby uncover said chute and render the multiple-ply web nearest to said platen accessible for manipulation.

31. In a multiple-ply-web-manifolding typewriting machine, the combination with a 65 revoluble platen, of means for presenting to

said platen and feeding therearound two superposed multiple-ply work-webs, each bearing a succession of forms, a paper-table adjacent the delivery side of said platen, a web-collating structure including a plurality of 70 web-separating and web-guiding plates over said table and forming therewith a chute for the multiple-ply web that is nearest to said platen, and means supporting said structure and manually rockable for displacing said 75 web-collating structure to thereby uncover said chute and render the multiple-ply web nearest to said platen accessible for manipulation, said web-collating structure having side-edge collating guides for the superposed web and being adjustable to the width 80 of said superposed web.
